UNITED STATES PATENT OFFICE.

MAXIMILIAN CHARLES SCHWEINERT, OF WEST HOBOKEN, NEW JERSEY, AND HENRY P. KRAFT, OF NEW YORK, N. Y., ASSIGNEES, BY MESNE ASSIGNMENTS, TO A. SCHRADER'S SON, INCORPORATED, OF NEW YORK, N. Y., A CORPORATION OF NEW YORK.

WATER-BOTTLE STOPPER.

No. 876,101.

Specification of Letters Patent.

Patented Jan. 7, 1908.

Application filed October 16, 1902. Serial No. 126,673.

To all whom it may concern:

Be it known that we, MAXIMILIAN CHARLES SCHWEINERT, residing at West Hoboken, in the county of Hudson and State of New Jersey, and HENRY P. KRAFT, residing in the city, county, and State of New York, citizens of the United States, have jointly invented certain new and useful Improvements in Water-Bottle Stoppers, of which the following is a specification.

In our application for patent, Serial No. 102,254, filed April 10, 1902, we have described certain disadvantages of the separable stoppers now generally used with hot-water bags, and have indicated various means for conveniently connecting the stopper to the bag by means of a retainer adapted to extend within the bag and to prevent the complete removal of the stopper. The present application is in part a division of said application, and contains besides the matter divided out from the parent application certain improvements in details hereinafter specified.

Referring to the accompanying drawings illustrating embodiments of the invention,—Figure 1 is a sectional elevation of a stopper with a retainer connected thereto, the stopper being shown in place in the mouth of an ordinary hot-water bag. Figs. 2, 3, 4 and 5 are similar views of different embodiments of the invention, omitting the bag. Fig. 6 illustrates a clip which may be used for detachably attaching the end of the retaining means to the stopper.

According to our present invention we provide a stopper, and a retaining means comprising a substantially rigid stem connected at its upper end to the stopper, extending into the bag, and engaged within the bag preferably by means of an enlarged inner end as hereinafter described so as to prevent complete separation of the stopper from the bag.

A feature of the invention consists in making the retainer of wire forming substantially a ring and having a looped portion giving it resiliency so as to permit squeezing it through the mouth of the bag without permanent distortion. Various other forms of retainer however may be used without departure from the invention.

In order to insert the retainer into the bag it is necessary to push the same in from the

outside, and for this purpose the rigid stem which we provide is much more convenient than a flexible connection would be. It is also less apt to wear the inside of the rubber bag.

Another feature of value is the making of the retainer attachable to and detachable from the stopper by hand, so that the retainers may be sold as separate articles of manufacture and may be attached to old stoppers by the users.

Referring to the accompanying drawings, A indicates the water bag or other suitable liquid receptacle made of rubber or similar flexible material having a neck B and a lip C extending up above the mouth to form a funnel. Within the neck of the bag is a socket D provided with a stopper seat which may be the lower flange E of the socket. The stopper F is provided with screwthreads engaging the threads of the socket D and may be screwed in place by means of a thumb-piece G at the top.

The retaining means or confiner for the stopper comprises a substantially rigid stem such as the wire H loosely connected at its upper end to the under side of the stopper, as by being passed through an aperture in a clip J which is detachably attached to a button K on the under side of the stopper. The stem H has at its lower end an integral yielding or collapsible substantially triangular enlargement L, the sides being tapered downward so as to facilitate the insertion of the confiner. The loose connection between the stem H and the stopper permits the enlargement L to be parallel with the sides of the bottle.

The rigid stem of the retaining means or confiner is not necessarily made of a single wire as shown in Fig. 1. It may consist of a pair of wires H' (Fig. 2) with their lower ends bent as shown at L' L' to form an enlargement analogous to the enlargement L of Fig. 1. The loose connection at the top may be made by merely passing the wires H' H' through the aperture of the clip J.

A third construction which is within our invention is shown in Fig. 3, in which a single wire H forms the rigid stem and is pivotally connected at its upper end to the stopper, said wire being passed through the aperture in the clip J; the enlargement at the lower end being formed in this case by a spiral con-

volution L^3 of the lower end of the wire. The same facility for insertion and resistance to withdrawal are found with this retainer as with those previously described, and the 5 loose connection at the top has the same function.

Instead of the different enlargements at the lower end of the stem H previously described, we may use a separate member consisting of a ring L^8 (Fig. 4) or of any other suitable form without departing from the generic invention. This ring may be suspended by a stem consisting of a single wire H as shown, or otherwise, and may be either 15 permanently or detachably fastened to the stopper, being shown as attached by means of a detachable clip J similar to that of Fig. 1. Or the enlargement or retainer at the lower end of the stem may be of the form 20 shown in Fig. 5, and we consider this form preferable to the others. It may be either integral with the stem H or formed separately and connected thereto. It comprises a wire forming substantially a ring L^4 25 pointed at its lower end to facilitate passing it through the mouth of the bag and having at its opposite end a loop M, preferably a spiral of two convolutions to give it resiliency and to permit squeezing it through the mouth 30 of the bag without permanent distortion. Such a retainer as this opposes considerable resistance to being withdrawn out of the mouth of the bag, but because of its pointed end is very easily started, and because of the 35 loop M yields readily to its being pushed entirely through the mouth of the bag. If formed separately from the stem, the entire ring may be made of a single piece of wire, preferably with its ends abutting and soldered together, though not necessarily so; if made integral with the stem the latter may be formed of a single wire as shown, which 40 is first bent to form one of the convolutions of the loop M and then passes to the side and 45 down to the lower end and thence up the opposite side, bending into a convolution whose end is attached to the lower end of the straight portion of the wire H, as shown.

It will be seen that our invention provides 50 a retaining means which is extremely simple and cheap, and which has many advantages in actual use. The stem of the retainer or confiner is somewhat longer than the lip C of the bag, and by reason of the flexible connection with the stopper the latter is permitted to hang over the edge of the lip when withdrawn, and in convenient position for reinsertion into the mouth. When the bag is closed there is no apparent connection between 55 the bag and the stopper. The parts within the bag are so light and small as to be unnoticeable and without objectionable effect. When the stopper is withdrawn and hung over the edge of the funnel there is no 60 substantial obstruction to the admission of

water. In screwing it into or out of its socket the entire retainer may turn with it, and is out of the way so as not to interfere with the hand of the person manipulating it.

Though we have described with great particularity of detail a number of retaining devices embodying our invention, yet it is to be understood that the invention is not limited to the particular forms illustrated and described. The details and combinations of the parts are variable within a great range by persons skilled in the art without departure from the invention. For example, it is not essential that an impositive connection should be used between the stopper and the bag. The stem of the retainer may be permanently attached within the bag without modification of the other features of the invention involved. Also the retaining means may be attached to stoppers of various other kinds than those illustrated, there being many well known equivalents therefor.

In application No. 181,253 filed by us on November 14, 1903 we have claimed certain retaining devices or features thereof which are not claimed herein.

What we claim is:

1. The combination with a stopper for water bags, of retaining means comprising a substantially rigid stem connected at its upper end to the stopper and adapted to extend into and to be engaged within the bag to prevent complete separation of the stopper from the bag, said retaining means being attachable to and detachable from the stopper by hand.

2. A retainer for water-bag stoppers, comprising a wire forming substantially a closed figure and having a looped portion giving it resiliency so as to permit squeezing it through the mouth of the bag without permanent distortion.

3. A retainer for water-bag stoppers, comprising a wire forming substantially a closed figure pointed at one end to facilitate passing it through the mouth of a bag and looped at its opposite end to give it resiliency and permit squeezing it through the mouth of the bag without permanent distortion.

4. A retainer for water bag stoppers, having means for engagement with a water bag, said retainer being adapted to permit screwing and unscrewing of the stopper, and to prevent complete separation of the stopper from the bag when removed from its socket, and being adapted when such stopper is removed to permit free filling and emptying of the bag, and means whereby the retainer may be connected to a stopper by hand.

5. A retainer for water bag stoppers, having means for engagement with a water bag, said retainer being adapted to permit screwing and unscrewing of the stopper, and to prevent complete separation of the stopper from the bag when removed from its socket,

and being adapted when such stopper is removed to permit free filling and emptying of the bag, and means whereby the retainer may be connected to and disconnected from a stopper by hand.

6. A retainer for water bag stoppers, having means adapted to extend within the bag, said retainer being adapted to permit screwing and unscrewing of the stopper, and to prevent complete separation of the stopper from the bag when removed from its socket, and being adapted when such stopper is removed to permit free filling and emptying of the bag, and means whereby the retainer may be connected to a stopper by hand.

7. The combination with a retainer for water bag stoppers adapted to prevent the complete separation of the stopper from the bag, of a stopper, a button on the bottom of said stopper, and means for detachably connecting said retainer to said button.

8. The combination with a retainer for water bag stoppers comprising a wire having ends converging inwardly and downwardly at the lower end to facilitate passing the same through the mouth of a bag, and adapted to extend within the bag to prevent a complete separation of the stopper from the bag, of means for detachably connecting said retainer to a stopper.

9. The combination with a water bag of soft flexible material, having a screw-threaded stopper, of a retainer engaging said bag and stopper so as in effect to swivel the stopper to the bag, whereby to permit the screwing and unscrewing of said stopper, said retainer being adapted to prevent complete separation of the stopper from the bag, and being adapted to permit the bag to be filled and emptied when the stopper is removed, and means whereby the retainer may be connected to the stopper by hand.

10. The combination with a water bag stopper having a portion of reduced diameter,

of a retainer therefor adapted to prevent the complete separation of the stopper from the bag, and means whereby said retainer may be connected to such reduced portion by hand.

11. A retainer for water bag stoppers or the like, adapted to engage a water bag and permit free screwing and unscrewing of the stopper, means whereby said retainer may be connected to the stopper by hand, and said retainer including means to prevent the complete separation of the retainer and bag, said last mentioned means being adapted to be inserted by hand into the bag.

12. The combination with a stopper for water bags, of a retainer therefor connected to the bottom of said stopper and adapted to extend within the bag and to prevent the complete separation of said stopper from the bag and to permit free filling and emptying of the bag when removed therefrom, said retainer being adapted for disconnection from said stopper by hand.

13. The combination with a stopper for water bags, of a retainer therefor, a button on the bottom of said stopper, said retainer being detachably connected to said button and adapted to extend within the bag and to prevent the complete separation of said stopper from the bag.

14. The combination with a stopper for water bags, of a retainer therefor detachably connected thereto and comprising wires converging inwardly at their lower end to facilitate passing the same through the mouth of a bag.

In witness whereof, we have hereunto signed our names in the presence of two subscribing witnesses.

M. CHARLES SCHWEINERT.
HENRY P. KRAFT.
